UNITED STATES PATENT OFFICE.

LOYD C. POWELL, OF CUSHING, OKLAHOMA.

COMBINED GRIP AND JACK.

Application filed August 16, 1923. Serial No. 657,799.

To all whom it may concern:

Be it known that I, LOYD C. POWELL, a citizen of the United States, residing at Cushing, in the county of Payne and State 5 of Oklahoma, have invented certain new and useful Improvements in a Combined Grip and Jack, of which the following is a specification.

This invention appertains to novel improvements in jacks and the primary object 10 of the invention is to provide a novel device for facilitating the raising and lowering of pipes into wells and the like.

Another prime object of the invention is 15 to provide a novel device, which is particularly adapted for lowering wall casings into wells, but which can be used as a lifting jack for vehicles and the like if desired.

A further prime object of the invention is 20 to provide an improved device of the above character embodying a supporting frame, means carried by the frame for gripping the pipe, an operating lever carried by the frame and novel means carried by the lever for 25 gripping the pipe for raising or lowering the same step by step, the pipe gripping means carried by the frame permitting the holding of the pipe during movement of the lever to obtain a new grip on the pipe.

A still further object of the invention is 30 to provide an improved device of the above character, which will be durable and efficient in use, one that will be simple and easy to manufacture, and one which can be placed upon the market at a small cost.

With these and other objects in view, the invention consists in the novel construction, arrangement and formation of parts, as will be hereinafter more specifically described, 40 claimed and illustrated in the accompanying drawings, in which drawings:

Figure 1 is a side elevation of the improved device.

Figure 2 is a fragmentary vertical section 45 through the same.

Figure 3 is a bottom plan view of the improved device.

Figure 4 is a horizontal section through 50 the improved device taken on the line 4-4 of Figure 1, and

Figure 5 is a detail section taken on the line 5-5 of Figure 3.

Referring to the drawings in detail, 55 wherein similar reference characters designate corresponding parts throughout the several views, the letter A generally indi-

cates the improved device and B a pipe, on which the same can be used. While in the drawings I have particularly shown the same in use for lifting pipes it is to be 60 understood that the same can be effectively used for lowering pipes and for other purposes.

The improved device A comprises a frame 10 including a pair of arms 11 and 12, which 65 are integrally connected together at their inner ends by a bight portion 13. The arms then extend forwardly in parallel relation as at 14 for a short distance and are then bowed arcuately as at 15 to provide means 70 for extending about the pipe and well and then forwardly in parallel relation again as at 16. This frame 10 is preferably held against movement in any preferred way at the top of the well hole. One of the straight 75 portions 14 of the arms 11 and 12 has riveted thereto a forwardly extending strap 17, which terminates at its outer end in a hook 18 for engaging the pipe. The other straight portion of the other arm has secured thereto a strap 19, which terminates short of the bill of the hook 18. Rockably 80 mounted upon a pin 20 intermediate the straps 17 and 18 is a dog 21 embodying spaced divergently extending pipe engaging 85 gripping teeth 22 and 23. If so desired a leaf spring 24 can be employed for normally throwing the dog 21 into engagement with the pipe, or the action of gravity solely can be utilized for normally moving the teeth 90 into pipe gripping position. Disposed between the straight portions 14 of the arms 11 and 12 adjacent to the connecting or bight portion 13 is a link 25. This link 25 supports a pivot bolt 27, which forms the fulcrum point of the operating lever 28. It can be seen that the lever is rockably mounted upon the pin 27 at a point intermediate its ends. The inner end of the lever 28 is of a 95 yoke shape as indicated by the reference characters 29 for receiving the pin 27 and the upper end of the link 25 therebetween and the extreme forward end of the yoke 29 carries a second pivot pin 30 on which is rockably mounted a U-shaped frame 31, 100 which is adapted to embrace the pipe to be raised. This frame 31 is preferably connected to the yoke end 29 of the lever 28 by means of a suitable spring 32, so as to normally hold the frame in substantial alignment with the lever. A dog 33 is also rockably 105 mounted upon the bolt or pivot pin 30

100

95

105

110

and this dog 33 is of substantially the same shape as the dog 21 and embodies divergently extending teeth 34 and 35. If so desired a chain 36 can be carried by the connecting portion 13 of the frame 10 and this chain can hook over the outer end of the lever 28 for normally holding the same in a predetermined position after the lever has been operated for lifting the pipe.

10 In operation of the improved device, for lifting pipes, the jack is slipped over the pipe in such a manner that the U-shaped frame 31 and the strap 17 will lie about the same. During the movement of the device 15 over the pipe B the dogs 21 and 33 are raised, so that the lower teeth 23 and 35 thereof will engage the pipe. The frame 10 is now rested on the lower surface of the ground over the well hole or upon any 20 other suitable support after which the outer end of the lever 28 is swung up, which will move the frame 31 downward over the pipe. Now upon downward movement of the outer end of the lever, the pipe will be raised due 25 to the fact that the tooth 35 will be forced into engagement with the pipe. The raising movement of the pipe will be permitted by the upward swinging movement of the tooth 23. As soon as this lifting movement has 30 been accomplished and the pipe B starts to slide back, the tooth 23 will be forced into firm contact therewith and thus hold the pipe against further movement. The lever is again operated to lift the pipe.

35 When it is desired to lower the pipe into the casing the position of the tool is reversed and the lever is then lowermost. In this contingency the teeth 22 and 34 will then engage the pipe. During the lowering movement of the pipe the lever 28 is operated in 40 the same manner as heretofore described.

From the foregoing description, it can be seen that I have provided a novel device of exceptionally simple and compact nature, 45 which will effectively accomplish the purpose intended.

Changes in details may be made without departing from the spirit or the scope of this invention.

What I claim as new is:

1. In a device of the character described, 50 a frame including a pair of integrally connected arms, the intermediate portions of the arms being bowed in opposite directions, a strap carried by the frame, a hook formed 55 on the strap for encircling the device to be raised and lowered, a double ended dog pivotally carried by the strap and arranged in opposite relation to the hook, a link pivotally secured to the frame, a lever pivotally secured intermediate its ends to the link, a U-shaped frame pivotally secured to the lever for embracing the device to be raised and lowered, and a double ended dog rockably carried by the lever for engaging the 60 device to be raised and lowered.

2. A jack comprising a horizontally disposed base frame, means carried by the frame for encircling the device to be raised, 65 a pivoted dog carried by said means for engaging the device to be raised, a link secured to the frame, an operating lever pivotally supported by the link, means carried by the inner end of the lever for encircling 70 the device to be raised, and a pivoted dog 75 carried by the lever for engaging said device.

3. A jack comprising an open horizontally disposed base frame, means carried by the base frame for releasably engaging the device to be raised or lowered, the device to 80 be raised or lowered being adapted to extend through the open frame, a link pivotally secured to the frame adjacent to one end thereof, an operating lever pivotally secured to the link at a point intermediate its ends, 85 means carried by the inner end of the lever for partially encircling the device to be raised or lowered, a pivoted dog carried by the lever for engaging the device to be raised or lowered, and means carried by the frame 90 for engaging the lever to hold the same in an adjusted position.

In testimony whereof I affix my signature in presence of two witnesses.

LOYD C. POWELL.
